FOLDABLE TABLE

Filed April 22, 1931

INVENTOR

Sigmund Kanclerz

UNITED STATES PATENT OFFICE

SIGMUND KANCLERZ, OF MASPETH, NEW YORK

FOLDABLE TABLE

Application filed April 22, 1931. Serial No. 531,903.

This invention relates to improvements in folding or collapsible tables, and it is the principal object of my invention to provide a table that may conveniently be folded into a comparatively small and compact parcel whereby the table plate forms parts of a case in which the table can be conveniently carried and in which ample space is left for allowing the storage of other articles such as for instance foldable chairs.

Another object of my invention is the provision of a collapsible table, all elements of which are firmly connected so as to form when set up as such a table of great strength securely supported at a convenient distance from the ground, yet allowing a ready collapsing.

A further object of my invention is the provision of a collapsible table readily convertible into a hat-box like structure conveniently to carry without by its outer appearance betraying its use as a table.

A still further object of my invention is the provision of a collapsible table of comparatively simple, and inexpensive structure, yet durable and efficient in operation.

These and other objects and advantages of my invention will become more fully known as the description thereof proceeds and will then be specifically defined in the appended claims.

In the accompanying drawing forming a material part of this disclosure:

Fig. 1 is a front elevation of a folding or collapsible table constructed according to my invention, set up as table.

Fig. 2 is a bottom plan view of the table plate in its unfolded position seen along line 2-2 of Figure 1.

Fig. 3 is a detail view of a slotted side bar and parts co-operating therewith.

Fig. 4 shows the table when collapsed representing a box- or case-like structure.

Fig. 5 is a section on line 5-5 of Figure 4.

Fig. 6 is a detail view of one of the table top supporting members.

As illustrated, the trunk consists of two parts 10 and 11, and a center part 12 to which the inner edges of the trunk are jointed or

hinged, as at 13, to allow a convenient closing of the trunk or box.

On plate 12 are arranged four upright pins 13' about which the four bars 14, 15, 16, and 17 are turned intermediate their ends.

In their table plate supporting position as shown in Figure 2, these bars engage with their inner ends in channel irons 18, 19, transversely arranged on the lower face of part 12, while their outer ends engage loops 20 on the lower face of the parts 10 and 11 of the box.

The irons 18, 19, support L-irons 21, 22, held at their ends by the bolts 13' to channel irons 18, 19. The bars 21, 22, are provided with longitudinally extending slots 23 near one of their ends of a transverse rod 24 connecting the outer ends of parallel bars 25, the inner ends of which are pivotally connected to the flanges 26, 27, of a plate 28.

To these flanges are also pivotally connected the inner ends of parallel bars 29, 30, the outer ends of which are connected by means of prongs 31 to the non-slotted ends of bars 21, 22, which for this purpose have holes to allow a removable engagement of prongs 31.

Intermediate their ends bars 29, 30, are connected by a bar 32 loosely guided with its ends in bars 29 and 30 and having a spring 33 wound about its part between bars 29, 30, tending to normally press the prongs into the holes in bars 21, 22.

A central bar 34 having a head 35 engaging plate 29 has slidably guided therein a sleeve 36 carrying a bracket 37, to the arms 38 of which are pivotally attached the inner ends of legs 39, the outer ends of which show feet 39. The box or trunk 10 has a handle 40 and snap locks 41 holding the parts in their closed position over the table folded therein.

As shown in Figure 5, spaces 42, 43, are provided for storing folding chairs or the like within the closed box.

In operation, if it is desired to fold the table, bars 14, 15, 16, 17, are released from their holders 20 by turning them about their pivot point 13' so as to engage under bars 21, 22, then prongs 31 are released from engagement with bars 29, 30. Bars 25, 26, and 28, 30 are pivotally connected at their inner

ends, as at 44, 45, respectively to the flanges of plate 28.

The legs 38 having been previously folded against stem 34 are prevented from spreading by a bracket 46 and are in their folded position together with stem 34 drawn inward laterally into the box while the pins 24 slide inwardly in slots 23 of bars 21, 22, so as to form a compact parcel 47.

10 It will be understood that I have disclosed one form of my invention as an example only, and that certain changes may be resorted to without departing from the spirit of the invention or the scope of the appended claims.

15 Having thus described my invention what I claim as new and desire to secure by Letters Patent is:

1. In a collapsible table a table top composed of two outer members and one inner member, to which the outer members are hingedly connected, a pair of transverse L-bars provided with holes at one end and with longitudinal slots on part of their length, at the other ends, a flanged plate, side bars attached at their outer ends to bolts sliding in said slots and at their inner ends pivotally secured to the flanges of said plate, a pair of other side bars, bolts on said last named side bars removably engaging the holes in said 20 L-bars, and a spring controlled transverse bar having its ends loosely mounted in said last

named side bars to allow a bringing together of said bars against the action of their spring for disengaging the bolts from said side bars, the inner ends of said side bars also pivotally connected to the flanges of said plate.

2. In a collapsible table, a flanged plate, two pairs of parallel bars having their inner ends connected to the flanges of said plate, outwardly curved outer ends on said bars, L-irons having longitudinally extending slots near one of their ends, and a plurality of perforations at their other ends, prongs at the outer ends of said pairs of parallel bars adapted to engage said perforations in the ends of said L-irons, a transverse rod guided with its ends in the longitudinal slots of said L-irons, a bar loosely guided with its ends in one pair of said parallel bars, and a spring wound about said loosely guided bar between said parallel bars to press the prongs of said last-named bars into the perforations of said L-irons, means for supporting said plate, and two outer table plate members hingedly connected to an intermediate inner plate, and collapsible means to support said two outer plate members in their extended position.

Signed at Maspeth, L. I., in the county of Queens and State of New York, this 9th day of April, A. D. 1931.

SIGMUND KANCLERZ.
